Primary Examiner — Mark Goodwin(74) *Attorney, Agent, or Firm* — Moser Taboada(57) **CLAIM**

The ornamental design for a AC module mounting bracket, substantially as shown and described.

DESCRIPTION

FIG. 1 is a perspective view of a AC module mounting bracket embodying the new design;

FIG. 2 is a front plan view of a AC module mounting bracket embodying the new design;

FIG. 3 is a rear plan view of a AC module mounting bracket embodying the new design;

FIG. 4 is a top plan view of a AC module mounting bracket embodying the new design;

FIG. 5 is a bottom plan view of a AC module mounting bracket embodying the new design;

FIG. 6 is a left side view of a AC module mounting bracket embodying the new design; and,

FIG. 7 is a right side view of a AC module mounting bracket embodying the new design.
